UNITED STATES PATENT OFFICE.

TAHVAN E. AHO, OF WAUKEGAN, ILLINOIS.

SHOE JACK.

Application filed October 4, 1927. Serial No. 224,005.

This invention relates to boot and shoe jacks upon which boots or shoes are inverted and placed for the purpose of holding the shoe during many of the different operations 5 in making or repairing.

The general object of the present invention is to provide a jack of this character having a standard supporting the last or other element upon which the shoe is placed, 10 which standard is mounted for rotation around a vertical axis and upon a base or mounted for oscillation in a vertical plane, this oscillatory movement, however, also permitting the base of the jack to be rotated 15 so that the standard in an inclined position may be rotated around a vertical axis.

A further object is to provide a jack of 20 this character which is adjustable into many different positions and my improved jack is, 25 as a matter of fact, adjustable into about fifty-six different positions.

A still further object is to provide a device of this character which may be adjusted so as to compensate for wear and which is 25 simple, strong and effective in actual use.

Other objects will appear in the course 30 of the following description.

My invention is illustrated in the accompanying drawings, wherein:

Figure 1 is a side elevation of a jack constructed in accordance with my invention;

Figure 2 is a vertical sectional view of the upper portion of the jack showing the upper section angularly disposed with relation to the lower section;

Figure 3 is an inside face view of the bracket;

Figure 4 is a section on the line 4-4 of Figure 1;

Figure 5 is a fragmentary section of the base portion of the jack showing the latch;

Figure 6 is a section on the line 6-6 of Figure 2;

Figure 7 is an inside face view of another form of bracket;

Figure 8 is an elevation of one of the locking pins;

Figure 9 is an elevation of the other locking pin.

Referring to these drawings, 10 designates a base plate having the legs 11, these legs being disposed in any suitable manner. The base plate is formed integral with an upwardly extending annular member 12 55 formed adjacent its upper end with a circum-

ferential recess 13. Surrounding this annular member 12 is a second annular member 14 having one or more set screws 15 which extend into the recess 13 and permit the annular member or sleeve 14 to be rotated 60 around the member 12.

Mounted upon the member 14 by screws 16 is a supporting bracket 17, the upper end of which is vertically slotted or bifurcated, as at 18, and crossing this slotted portion is the transverse pin 19 constituting a pivot pin. The inner face of the plate or bracket 17 is recessed, as at 20, this recess accommodating the cylinder 14. Pivotedly mounted upon the bracket 17 is a cylinder 21 which is adapted to align with and seat upon cylinder 14. This cylinder 21 carries the sector 22 through which the pivot pin 19 passes, and the sector is formed with a plurality of perforations 23 arranged in a series concentric to the pivot 19 into which a spring-projected locking pin 24 engages, this locking pin being mounted upon and carried by the bracket 17 having a head 25 whereby the locking pin may be retracted against the action of the spring 26. By this means the cylinder 21 may be supported upon the bracket in any desired angular position.

Disposed within the cylinder 21 is a cylindrical section 27 having a head 28 which extends over the upper end of the cylinder 21 and is formed with a series of spaced bolt-receiving apertures 29 for engagement by a sliding bolt 30 mounted in the upper end of the web or sector 22 and projected by means of the spring 31. This bolt has the head 32 whereby it may be retracted. This spring is held in place by the plate 33 attached by screws or other suitable means to the sector web 22. The cylindrical member 27 adjacent its lower end is formed with a circumferential groove 34 and cylinder 21 is formed with one or more set screws 35 extending into this recess so that the cylindrical member 27 may be rotated around 90 its axis but cannot be pulled out.

The member 27 does not extend down through the full depth of the cylinder 21 and is provided with the many-sided tapering bore or socket 36 within which the 105 tapering lower end of a standard 37 is disposed. The upper end of this standard carries the metallic or other last 38. It will be understood that the cylindrical member 14 is rotatable around the cylinder 12, which 110

last cylinder forms part of the base 10. This cylinder 12 is formed with a slot 39, and pivoted within the lower end of the cylinder 12 is a latch 40 urged to a raised position by 5 a spring 41, the nose of this latch extending through the slot 39 and into any one of a series of notches 42 formed in the lower end of the cylinder 14. When this latch is depressed out of any one of these notches 42, 10 the cylinder 14 may be rotated, carrying with it the bracket 17, and the structure supporting the standard 37 and the last.

For the purpose of depressing this latch 40, I provide the depending rod 43, which 15 at its lower end is connected to a treadle 44 pivotally mounted in brackets 45 on the floor. By this means the workman can at any time release the latch 40 and then turn the cylinder 14 to carry the shoe into any 20 desired position. By pulling out the latch or bolt 24, the upper section may be oscillated in a vertical plane to dispose the standard at any desired angle. By pulling out the bolt 30, the cylindrical base member 27 25 for the standard may be rotated around the longitudinal axis of the standard so as to rotate the shoe around this axis. Thus it will be seen that with the construction described a large number of different adjustments may be made, each adjustment being 30 independent of any other adjustment, so that the work may be presented in the best possible fashion to the workman. As a matter of fact, and as before stated, there are some 35 fifty-six different positions into which the standard as a whole may be adjusted.

In Figure 7, I illustrate another form of bracket 10^a. This bracket 10^a has approximately the same form as the bracket 17 and 40 is formed with a slot 18^a and a transverse pin 19^a, but in place of the latch bolt 24 there is provided a pivoted latch 46 pivotally mounted in a slot 47 upon a pin 48 and having the depending portion 49 engaged 45 by a coiled contractile spring 50 which urges the latch upward. The latch has a portion 51 adapted to engage in transverse recesses or teeth formed in the sector 22 and the latch is extended laterally so as to form a 50 thumb piece 52. A stop 53 limits the downward movement of the latch.

The operation of the general mechanism is the same whether the latch means shown in Figure 7 be used or the latching bolt 24 be 55 used. A stand constructed in accordance with my invention may be made for a considerably less sum than the ordinary jack or stand and gives better and quicker results at a lower cost. The stand completed weighs 60 about fifty-five pounds and this is about one-half the weight of ordinary stands. The adjustments may be made with a minimum of effort and time and the parts which are likely to wear down can be adjusted by 65 adjusting six set screws. No dirt can enter the

stand for the reason that the interior parts are thoroughly protected. If any dirt should drop into the interior of the cylinder 12, it will pass through onto the floor.

It will be obvious that many modifications 70 might be made in the details of construction and arrangement of parts without departing from the spirit of the invention as defined in the appended claims.

I claim:—

1. A shoe jack of the character described comprising a base, a member mounted for rotation upon the base around a vertical axis and carrying an upwardly extending bracket, and a hollow, cylindrical member mounted upon said bracket for tilting movement, a cylindrical member mounted within the first named cylindrical member for rotation around an axis common to both of said members and having a socket for the 55 reception of a shoe last supporting standard, and means for locking the second named cylindrical member in any rotatively adjusted position.

2. A shoe jack of the character described 90 comprising a base, a member mounted for rotation upon the base around a vertical axis and carrying an upwardly extending bracket, and a member mounted upon said bracket for tilting movement and carrying a 95 shoe last supporting standard, the standard being mounted for rotation within said last named member around its own longitudinal axis, treadle-released means for holding the first named member locked in any rotatively 100 adjusted position, means for locking the second named member in any tilted position, and means for locking the standard in any rotatively adjusted position.

3. A shoe jack comprising a base having a 105 cylindrical member mounted thereon, a hollow cylinder mounted for rotation around the cylindrical member, treadle-released means for latching the cylinder in any desired rotative position, a bracket mounted 110 upon the cylinder and projecting above the same, a hollow cylindrical member mounted upon the bracket for oscillation in a vertical plane, a cylindrical member disposed within the last named hollow cylindrical member 115 and rotatively mounted therein and having a socket for a last-supporting standard, a last-supporting standard extending into said socket, means for locking the last named cylindrical member in any rotatively adjusted position, and releasable means for holding the cylindrical member mounted upon said bracket in any tilted position.

4. A shoe jack comprising a base having 120 a cylindrical member mounted thereon, a cylinder mounted for rotation around the cylindrical member, treadle released means for latching the cylinder in any desired rotative position, a bracket mounted upon the cylinder and projecting above the same, a 125

cylindrical member mounted upon the bracket for oscillation in a vertical plane and carrying a last supporting standard, releasable means for holding the member 5 in any tilted position, a standard, a base for the standard rotatably mounted within said tiltable member for rotation around the longitudinal axis of the standard, and means for holding said standard base in any 10 rotated position.

5. A shoe jack of the character described comprising a base having an upstanding cylindrical portion, a cylinder surrounding the cylindrical portion and having rotation 15 therearound, said cylinder supporting an upstanding bracket, a second cylinder having a sector formed therewith, the sector being pivoted in said bracket whereby the second named cylinder may be shifted into 20 a tilted position or into a position of alignment with the first named cylinder, means engaging the sector for latching the second named cylinder in any angularly adjusted position, a cylindrical base mounted within 25 the second named cylinder for rotation around the axis of the cylinder and carrying a standard for supporting a last, means for latching the base in any rotatively adjusted position, and pedally released means for 30 latching the first named cylinder in any rotated position.

6. A shoe jack of the character described comprising a base having an upstanding cylindrical portion, a cylinder surrounding the cylindrical portion and having rotation 15 therearound, said cylinder supporting an upstanding bracket, a second cylinder having a sector formed therewith, the sector being pivoted in said bracket whereby the second named cylinder may be shifted into a tilted position or into a position of alignment wth the first named cylinder, means engaging the sector for latching the second named cylinder in any angularly adjusted position, a cylindrical base mounted within the second named cylinder for rotation around the axis of the cylinder and carrying a standard for supporting a last, means for latching the base in any rotatively adjusted position, pedally released means for 50 latching the first named cylinder in any rotated position, including a latching member

resiliently urged into latching position, and a treadle operatively engaged with the latching member to retract the same against the 55 action of the spring.

7. A shoe jack comprising a base having legs, the base being formed with a cylindrical upstanding portion, a cylinder surrounding the upstanding portion and rotative 60 around the same, the cylinder at its lower end being formed with a plurality of circumferentially arranged recesses, a bracket mounted upon the cylinder and extending above the same and bifurcated at its upper 65 end, a second cylinder disposed above and adapted to seat upon the upper edge of the first named cylinder and pivotally mounted upon the bracket for tilting movement, means for holding the second named cylinder 70 in any one of a plurality of tilted positions upon said bracket or holding it in alignment with the first named cylinder, a cylindrical base member mounted within the second named cylinder for independent rotation and having a head extending over the second named cylinder, a standard mounted in said base member and extending upward therefrom and supporting a shoe last, means for holding the base member in any 75 one of a plurality of rotated positions, the first named cylinder having notches, and a pedally released latch mounted upon the base member and yieldingly urged into engagement with any one of said notches. 85

8. A shoe jack of the character described comprising a base, a member mounted for rotation upon the base around a vertical axis and having an upwardly extending bracket, a member mounted upon said 90 bracket for tilting movement and carrying a shoe last supporting standard, a spring actuated latch for said member whereby it may be locked in any one of a plurality of tilting positions, the first named member 95 being formed with a plurality of notches disposed concentrically to the axis of rotation of the member, and a treadle released latch yieldingly urged into engagement with the notches. 100

In testimony whereof I hereunto affix my signature.

TAHVAN E. AHO.
